CLAIM

The ornamental design for a rear license plate finish panel of a truck vehicle, as shown and described.

DESCRIPTION

FIG. 1 is a FRONT AND RIGHT SIDE PERSPECTIVE view of a rear license plate finish panel of a truck vehicle showing our new design;

FIG. 2 is a TOP PLAN view thereof;

FIG. 3 is a BOTTOM PLAN view thereof;

FIG. 4 is a FRONT ELEVATION view thereof; and,

FIG. 5 is a RIGHT SIDE ELEVATION view thereof.

The broken lines in the drawing depict environmental subject matter and form no part of the claimed design.
